Primary Examiner — Steven J Czyz*(74) Attorney, Agent, or Firm* — Wolf, Greenfield & Sacks, P.C.(57) **CLAIM**

The ornamental design for a door lock, as shown and described.

DESCRIPTION

FIG. 1 is an upper, front, right perspective view of a door lock;

FIG. 2 is a front view thereof;

FIG. 3 is a rear view thereof;

FIG. 4 is a left side view thereof;

FIG. 5 is a right side view thereof;

FIG. 6 is a top view thereof; and,

FIG. 7 is a bottom view thereof.

The dash-dash lines depict portions of the article that form no part of the claimed design; and the dash-dot-dash lines represent boundaries of the claimed design and form no part thereof.

1 Claim, 5 Drawing Sheets(56)
